United States Patent [19]

Iino

[11] Patent Number: Des. 313,977

[45] Date of Patent: ** Jan. 22, 1991

[54] ELECTRONIC COMPUTER

[75] Inventor: **Masaaki Iino**, Yokohama, Japan

[73] Assignee: **Kabushiki Kaisha Toshiba**,
Kanagawa, Japan

[**] Term: 14 Years

[21] Appl. No.: 276,438

[22] Filed: Nov. 23, 1988

[30] Foreign Application Priority Data

May 24, 1988 [JP] Japan 63-20165

[52] U.S. Cl. D14/106; D14/100

[58] Field of Search D14/100, 106, 107, 113,
D14/115; D18/1, 7, 11, 12; 235/145 A, 145 R;
312/208; 340/700, 706, 711, 712; 341/22, 23;
358/249, 254; 364/706-710; 400/489, 492, 496
